UNITED STATES PATENT OFFICE

WILLIAM CHARLES KLUNK, OF ST. LOUIS, MISSOURI, ASSIGNOR TO H. R. WEBB NECK-WEAR & MFG. CO., OF ST. LOUIS, MISSOURI, A CORPORATION OF MISSOURI

NECKTIE

Application filed April 29, 1929. Serial No. 358,983.

This invention relates to a certain new and useful improvement in neck ties of the kind known as four-in-hand ties, and has for its main object to provide improved means for securing the small or rear end to the large or front end of the tie for holding the ends of the tie together after being made up and worn by the wearer.

Another object of the invention is to provide the tie with improved means forming a part of the tie for joining the large and small ends of the tie together while being worn so that both ends will depend together and form a single depending end to the tie which will tend to hold the tie in a straight position.

Other and further objects will appear in the specification and be specifically pointed out in the appended claims, reference being had to the accompanying drawings, exemplifying the invention, and in which:

Figure 1 is a front view of a made up four-in-hand tie attached to a collar showing this improvement applied to the tie.

Figure 2 is an enlarged rear view of a tie having the intermediate portion broken away, before it is made up.

Figure 3 is an enlarged rear view of a folded tie showing the manner of securing the small end thereof to the large end.

Referring by numerals to the accompanying drawings the tie 1 is made of the usual tie material which is shaped in the form of a tubular type and secured by the stitching 3 on the rear side 4 of the tie.

The small end 5 of the tie is narrower in width than the large end 6, said ends 5 and 6 also being called the rear and front ends respectively of the tie, an end of the folded portions on the rear side of the large end 6 of the tie being free from the securing stitching 3 so as to form a flap 7.

Formed in the flap 7 is a transversely inclined slit 8 which is bound by button hole stitching 9 for reinforcement, said slit being

for cooperation with the small end 5 of the tie.

In the use of a four-in-hand neck tie having this improvement thereon, after the tie has been made up as shown in Fig. 1, the small or rear end 5 of the tie is engaged by one hand of the wearer and the other hand is used to underengage the flap 7 for manipulation so as to enter the small end 5 of the tie in the slit and pull the small end through the slit beneath the flap 7 as shown in Fig. 3. This securing of the small or rear end 5 of the tie in the slit 8 will securely hold the small end from spreading and flapping and in addition will tend to provide body weight to the depending portions of the tie and will serve to position or hold the tie in a straight position while being worn.

It is to be noted that the slit 8 is disposed angularly in the flap 7, in this instance of showing in the drawings. This is for the purpose of providing length to the slit which otherwise could not be done by reason of the narrowness of the flap 7 and in some instances the slit may be made as inclining from the vertical so as to provide a reasonably long slit in a comparatively narrow tie near the bottom of the large end 6 of the tie.

The slit or elongated opening 8 is made less in length than the width of the small or rear end 5 of the tie so that the flared end of the tie must be crumpled to reduce the width in order to pass through the slit 8, and after insertion of the end 5 has been made in the slit 8, the flared portion of the small end of the tie can be spread to its full width so that the inserted end will then be wider than the length of the slit 8. This wider portion of the end 5 of the tie after being inserted in the slit will tend to prevent the small end from working from the slit 8.

What I claim is:

1. A tubular four-in-hand neck tie having a large end and a small end; longitudinal stitching securing the edges on the rear of

the tie and terminating a distance from the large end of the tie, providing a free flap on the rear of the large end; said flap formed with a slit for the reception of the small end of the tie.

5 2. A tubular four-in-hand neck tie having a large end and a small end; longitudinal stitching securing the overlapped edges on the rear of the tie to a point spaced from the 10 end of said overlapped edges on the large end of the tie, providing a free flap on the rear thereof; the rear of the large end being formed with a slit adjacent an edge of the free flap which is made accessible by the free flap, for the reception of the small 15 end of the tie.

WILLIAM CHARLES KLUNK.
